US0D1099543S

(12) United States Design Patent (10) Patent No.: US D1,099,543 S
(45) Date of Patent:  Oct. 28, 2025

(54) BAG CHARM

(71) Applicant: Jiazhihao Network Technology (Guangzhou) Co., Ltd., Guangzhou (CN)

(72) Inventors: Jiale Wang, Guangzhou (CN); Xiaorui Yang, Guangzhou (CN)

(73) Assignee: Jiazhihao Network Technology (Guangzhou) Co., Ltd., Guangzhou (CN)

() Term: 15 Years

(21) Appl. No.: 29/926,616

(22) Filed: Jan. 31, 2024

(51) LOC (15) Cl. 11-01

(52) U.S. Cl.

USPC D11/82; D11/79; D3/211

(58) Field of Classification Search

USPC D3/207, 211; D8/331; D11/79, 82

CPC A47G 29/10; A44C 25/007; A45C 13/023

(57) CLAIM

The ornamental design for a bag charm, as shown and described.

DESCRIPTION

FIG. 1 is a perspective view of a bag charm, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view with shackle unlocked. The broken lines showing of the bag charm is for the purpose of illustrating portions of the article and forms no part of the claimed design.

1 Claim, 8 Drawing Sheets
